BOTTLE OPENING TOOL

Samuel G. Forman, Sr., and Samuel G.
Forman, Jr., Hightstown, N. J.

Application March 24, 1936. Serial No. 70,688

3 Claims.

(Cl. 30—3)

This invention relates to improvements in combination tools, and pertains particularly to a tool designed to facilitate the opening of bottles having sealed caps.

5 The majority of bottles in which fluids are put up for sale are provided with metallic or other forms of screw caps which, after being applied to the mouth of the bottle, are sealed by having a covering of some congealable substance placed thereover, which substance not only completely covers the cap but covers a portion of the bottle neck so that the cap cannot be removed until the sealing substance has been cut away. The removal of this sealing substance is often 10 difficult unless a proper instrument is employed and even then after the sealing substance has been cut away difficulty is often experienced in loosening or unscrewing the cap.

15 The primary object of the present invention is to provide a combination tool by means of which the above described difficulties associated with the opening of a screw-capped and sealed bottle can be easily and quickly overcome by providing means for cutting the sealing material and gripping and unscrewing the cap.

20 Another object of the invention is to provide a compound tool in which the several separate elements necessary for performing the operations of cutting loose the cap sealing material and of gripping and turning the cap, are conveniently 25 coupled together so that any desired one may be easily and quickly brought into operation.

25 Another object of the invention is to provide in association with a tool of the above described character means whereby the screw cap may be readily restored to its normal tight condition upon the bottle mouth from which it has been removed.

30 The invention will be best understood from a consideration of the following detailed description taken in connection with the accompanying drawing forming part of this specification, with the understanding, however, that the invention is not confined to any strict conformity with the 35 showing of the drawing but may be changed or modified so long as such changes or modifications mark no material departure from the salient features of the invention as expressed in the appended claims.

35 In the drawing:

40 Figure 1 is a view in plan of the tool embodying the present invention, the several elements of which have been separated so as to readily show the forms of the same.

45 Fig. 2 is a sectional view taken on the line 2—2

of Fig. 1, showing the manner of applying the tool to a bottle cap.

50 Fig. 3 is a view in plan of the bottle cap replacing portion of the tool.

55 Referring now more particularly to the drawing the numerals 1 to 4 inclusive indicate the several elements making up the present compound tool, each of which elements comprises a handle 5 which forms an integral extension of a body portion 6, and the body portions of the elements are normally disposed one upon the other, as illustrated in Figure 1 and are pivotally coupled together by means of the bolt 7 which passes therethrough, and is secured by the nut 8.

60 The body portion of the element 1 is provided with an arcuate head 9, the concave face of which is toothed or serrated, as indicated at 10, and constitutes a means for gripping, in association with another element, the cap of a bottle.

65 The element 2 which lies beneath the element 1 has a ring-like head 11 formed integral with its body portion and beneath this the element 3 has the arcuate head 12, the inner or concave surface of which is sharpened to form a cutting blade 13. The ring-like head 11 of the element 2 and 70 the heads 9 and 12 of the elements 1 and 3 respectively, are all formed upon the same radius so that when the handle portions of these elements are disposed in parallel superposed relation, the radial centers of the heads will be in 75 line.

80 The element 4 constitutes the bottom 1 of the group and is provided with the annular head 14 which is broken at spaced intervals by the impressed points 15 which are designed to engage 85 in the grooves which are formed vertically along the outer face of a bottle cap.

85 In the use of the present compound tool the several elements are separated in the manner illustrated in Fig. 1 and the annular ring-like head 11 which forms an axis about which the other heads turn, is slipped over the cap of the bottle. This cap is indicated by the numeral 16 in Fig. 2 and is shown applied to a bottle neck 17 and covered by the usual sealing material 18 90 which extends down beyond the lower edge of the cap in the manner illustrated. After the pivot head 11 is placed over the cap the knife head 12 is swung in until the edge of the blade 13 cuts 95 through the sealing material 18 as illustrated 50 in Fig. 2, whereupon the entire tool is rotated, or the tool may be held and the bottle and cap rotated so as to effect the cutting of the sealing material completely around the cap. After the sealing material has been cut, the gripping head 9 55

is swung in until its toothed inner face engages one side of the cap, forcing it to the opposite side of the pivot head 11 and holding the cap firmly against movement relative to the tool. By then holding the bottle firmly and turning the tool in the proper direction the cap 16 may be loosened and removed.

In the use of the cap replacing element 4 of the tool, it is preferred that the same be removed from the bolt 7 and used alone, as illustrated in Fig. 3. This tool is used by sliding its head over the cap after the sealing material 18 has been removed therefrom, so that the impressed points of the teeth 15 will engage in the grooves formed in the outer face of the cap and thus form a locking connection whereby the cap may be rotated and drawn up tightly upon the bottle neck.

From the foregoing it will be apparent that with the present tool, it will be a relatively simple matter to cut loose the material with which the bottle caps are usually sealed to the bottle neck, and effect the removal of the cap as well as its replacement.

We claim:

1. A tool of the character described, comprising an annular member adapted to encircle a bottle cap, a handle connected with said member and extending axially therefrom, a cutting element connected with the annular member and movable relative thereto for engagement with the side of a bottle cap while the annular member is in encircling relation therewith, and a handle car-

ried by the annular member which is movable relative to the first handle.

2. A bottle cap removing tool comprising an annular member designed to receive the cap, a handle connected with the member and extending axially therefrom, an arcuate element oscillatably connected with the annular member, said element having the concave edge thereof formed for working engagement with the cap, and a handle connected with said element and lying in a parallel plane with the first handle, whereby the element may be oscillated relative to the annular member.

3. A tool of the character described, comprising an annulus adapted to encircle a bottle cap, a handle integral with and extending radially from the annulus, a pivot member carried by the handle adjacent to the annulus, an arcuate body having an inner edge conforming in contour to the inside curvature of the annulus, said arcuate member merging at one end into a straight handle which is disposed in a parallel plane with the handle of the annulus and which has an aperture to receive said pivot member whereby the two handles may be oscillated relatively into a parallel relation, the inner edge of said arcuate member being formed for the performance of a desired working action upon a bottle cap disposed within the annulus.
